UNITED STATES PATENT OFFICE.

FRANK O. STERRETT, OF COLORADO SPRINGS, COLORADO.

CONCENTRATOR.

1,263,956.

Specification of Letters Patent. Patented Apr. 23, 1918.

Application filed October 2, 1914. Serial No. 864,642.

To all whom it may concern:

Be it known that I, FRANK O. STERRETT, a citizen of the United States, residing at Colorado Springs, in the county of El Paso and State of Colorado, have invented certain new and useful Improvements in Concentrators, of which the following is a specification.

My invention relates to apparatus for treating placer sands, tailings, or any material containing values, which may be separated therefrom mechanically because of the difference in their specific gravities, and has for its object to provide certain improvements in the construction and operation of the apparatus, as will be hereinafter more definitely pointed out and claimed, reference being had to the accompanying drawings, in which:—

20 Figure 1 is a vertical longitudinal sectional view of my improved concentrator, taken on line I—I of Fig. 2.

Fig. 2 is a top plan view of the same.

25 Fig. 3 is a vertical transverse sectional view, taken on the line III—III of Fig. 2.

Fig. 4 is a detail sectional view of one of the belt rollers.

30 Fig. 5 is an enlarged detail view partly in section of the vibrating mechanism for the concentrating belt and its carrier.

Fig. 6 is a diagrammatic view illustrating my improved apparatus in assembled connection with a wet screen for the material, the two producing a unit or body.

35 Similar numerals of reference denote corresponding parts in the several views.

In the said drawings, the reference numeral 1 denotes a tank or chamber, which may be of wood, metal or other suitable 40 material and braced in any desired manner. Said tank preferably is mounted on wheels 2, whereby it may be run on a track 3 for convenience in transportation and operation.

45 At one end at its bottom, the tank 1 is provided with a transverse partition 4, between which and the adjacent end of the tank is disposed a screw conveyer 5 adapted to convey material dropped thereon out at one side of the tank, where it will be taken up by a 50 bucket conveyer 6, disposed at an angle on one side of the tank 1 in a casing 7. The bottom of the tank 1 is also provided with a vertical transverse partition 8, supporting one end of an inclined false bottom 9, extending to the other end of the tank, said 55 tank having disposed therein at said end

another transversely disposed screw conveyer 10 adapted to feed the material through the side of said tank to a bucket conveyer 11 disposed in a casing 12. Within 60 the tank 1 are located two angle brackets or supports 13, one of the same being bolted to one side of the tank, and the other being bolted to and carried by a support 14 within the tank, and located some distance from its 65 opposite side. Said brackets 13 carry at their upper bent ends the bearings 15 for the central shaft 16 of a belt concentrator. This belt concentrator embodies side frames 17 suitably braced and carrying at its ends the 70 shafts 18 of drums 19, around which the concentrating belt 20, hereinafter described, is disposed, and by which the same is run. The drums 19 may be of any suitable construction, and in Fig. 4, I have shown them 75 as formed of end pieces 21 and an intermediate bracing member 22, the space between the end pieces 21 being covered by a spool of sheet metal wrapped therearound, and around which the belt 20 is disposed. While 80 said concentrating belt is supported centrally upon the shaft 16, it is also supported adjustably at its ends, the lower end being supported by chains 24 attached to each of the side frames 17 by links 25, said chains at their 85 upper ends being supported by screw threaded hooks 26 passing through a transverse cleat 27 on the top of the tank 1, and being capable of minor adjustment by means of a nut 28. Links 29, similar to the links 25, and 90 bolts 30 passing through a transverse cleat 31, support the upper ends of the side frames, the bolts 30 passing freely through the cleats 31 and being retained in place by nuts 32, springs 33 being interposed between 95 said nuts and the top of the cleat, whereby a yielding action is imparted to said bolts 30 and the upper end of the belt conveyer, as readily will be understood.

Power is applied to the device from a 100 main shaft 34 driven from a power pulley 35 and disposed longitudinally of and outside of the machine at one side thereof at the top, and supported in suitable bearings 36, mounted on the cleats 27 and 31, and also 105 on additional transverse cleats 37. At its end opposite the power pulley 35, the shaft 34 has mounted thereon a pulley 38 from which a belt 38' runs transversely of the machine to a similar pulley 39, mounted upon 110 a shaft 40 carried in bearings 41 upon the cleats 31 and 37 upon the opposite side of

the machine from, but parallel to, the main shaft 34. At its inner end this shaft 40 is provided with a wheel 42 to which is eccentrically connected a rod 47, by means of a pin 48, said rod extending downwardly and being connected at its lower end with a bell crank 49, mounted upon a bracket 50 attached to the side of the tank 1. The opposite arm of said bell crank 49 is pivotally connected 10 with the outer end of a bifurcated arm 51, the ends of the latter passing freely through plates 52, which in turn are movably disposed upon the reduced end 53 of the shaft 16 of the belt conveyer, said reduced end 53 15 carrying a nut 53' fixed thereon. Disposed between the plates 52 and surrounding the bifurcated ends of the arm 51 are coiled springs 54, while upon the outer ends of said arms are nuts 55, similar nuts 56 being fixed 20 upon said arms outside of the outer plates 52.

The drive for the belt 20 is provided from the drive shaft 34 through a pulley 57 on said shaft 34 intermediate its length, a belt 58 running from said pulley to a similar 25 pulley 59, carried by a shaft 60, that in turn is provided with a worm 61 meshing with worm gear 62, fixed to a transverse shaft 63, said pulley 59, shaft 60 and worm 61 being carried by a suitable bracket 64 mounted 30 upon the outside of the tank 1. The transverse shaft 63 extends within the tank and part way across the same, terminating at a bracket 65 bolted to the underside of a transverse bolster 66 that in turn is fixed to the 35 underside of the cleats 37. This bracket 65 carries a sprocket wheel 67 around which a sprocket chain 68 is carried and which in turn passes around a larger sprocket wheel 69 freely mounted on the shaft 16 of the 40 concentrator table. Also mounted upon said shaft 16 but keyed to the sprocket wheel 69 is a smaller sprocket wheel 70 from which a sprocket chain 71 passes to a similar sprocket wheel 72 at the upper end of the 45 belt conveyer, said sprocket wheel 72 being fixed to the shaft 18 of the upper drum around which the belt passes so that said drum will be driven thereby, and the motion of said drum imparted to the belt 20.

50 A suitable feed chute 73 is provided for the machine, the material being dumped upon the table 74 at the upper end thereof and fed into said chute, the lower end of said chute preferably terminating just above the 55 surface of the belt 20 at substantially its longitudinal center.

In operation the tank 1 is filled with water to the level of the dotted line in Fig. 1, which will just submerge the belt conveyer. 60 Motion is imparted to the drive shaft 34 from pulley 35 by any suitable source of power, which in turn, through the sprocket chain 68 and the connections hereinbefore described, will impart motion to the belt 20, 65 the relative adjustment of the parts of the

machine being such that the movement imparted to said belt will be comparatively slow, say three feet per minute, the upper surface of said belt traveling upwardly, in the direction of the arrow in Fig. 1. The material to be treated being fed through the chute 73, preferably in a wet state, will be deposited upon the belt 20 at substantially its center, and beneath the water level, where the action of the water will be to permit the gold or other values, on account of their greater specific gravity, to be deposited immediately upon the belt, and will cause the gangue to overlie said values and be carried gradually down the belt. As shown in Fig. 75 2, I have provided the outer surface of my belt 20 with a series of curved pockets or 80 riffles 78, said pockets or riffles being disposed transversely of the belt and being deeper at their centers than at their edges, in fact at their edges merging preferably into the surface of the belt. The action of these pockets or riffles 78 is to catch and retain the values, permitting the gangue to be washed over the same and down the belt, 90 said values being retained in said pockets until the pockets pass over the upper end of the conveyer, when said values are dumped onto the lower end of the false bottom 9, in position to be carried out by the conveyer 95 10. In order that there may be a most effective separation of the values from the gangue, the conveyer is given a bodily oscillatory movement by means of the rod 47 driven as hereinbefore described, said rod 100 through the bell crank 49 and the bifurcated arm 51 imparting to the shaft 16, on which the side frames 17 of the belt conveyer are fixed, a gentle but rapid oscillatory movement. It will be understood that the eccentric movement of the rod 47 will impart a reciprocating movement to the bell crank 49, which in turn will be imparted to the bifurcated arm 51, and because of the spring connection between said arm and the shaft 16, said motion will be imparted to said shaft but will be cushioned most efficiently. Thus upon a movement of the arm 51 inwardly, the outer plate 52 will be forced 110 away from the nut 53' on the reduced portion 53 of the shaft 16 and will tend to compress the springs 54 against the inner plate 52, thereby imparting a transverse bodily movement to the shaft 16 but with a cushioned effect. Similarly upon a movement 115 of the bell crank 49 in the opposite direction, the inner plate 52 will tend to be carried away from the shaft 16, thus again compressing the springs 54, said movement being resisted by the outer plate 52 in its contact with nut 53', and the shaft 16 will be moved in that direction, but with a similar cushioning effect. The result of this mechanism is that the conveyer belt and its supporting frame are given a rapid but cushioned 120 125 130

ioned bodily reciprocating movement while said belt is traveling on its pulleys, the result being that the separation of the values from the gangue is more readily effected, as 5 will be well understood by those skilled in the art.

By mounting the belt conveyer upon the shaft 16 and supporting its ends as described, I provide for a better disposition 10 of the weight of said carrier. Its immersion in the tank will naturally decrease its specific gravity, and by suspending its four corners in the manner shown, the weight of the same is lifted from the central shaft 15 16 and the belt may be run with very much less power than would be required with the same supported from beneath. Furthermore, by cushioning the support of the upper ends of the belt conveyer through the 20 springs 33, it will be evident that I further minimize the jar upon the belt 20, due to its rotation and to its bodily reciprocating movement hereinbefore described. In fact by cushioning the blow of the reciprocation 25 imparted to the conveyer and by supporting it resiliently at its upper end, so as to take off the weight of the same from the central shaft 16, I have provided a construction which in practice has obtained a maximum 30 effect in the separation of the values. Thus, while I obtain the movements heretofore deemed necessary in concentrating tables, at the same time I produce them in a manner to minimize the shock, whereby 35 values are not thrown from the side of the table, and at the same time produce sufficient jar to deposit the values at the lower-most points in the curved riffles 78 described. It will be understood that in the concentration 40 of values under water the lighter material will leave the table immediately upon being deposited upon the same from the chute 78, and will be held in suspension or in a state approximating the same, this effect 45 being carried out with the lighter material down to the heavier, which, of course, are the values. For this reason with a still body of water and a belt moving at a comparatively slow speed, and at the same time being subjected to a gentle but rapid vibration, and being cushioned against excessive jars in any direction, I effect a most 50 complete separation of the values from the ore, and deposit the same as a concentrate 55 over the upper drum 19 and at the lower end of the falst bottom 9, where the same may be removed by the screw conveyer 10. In fact I have found that the cushioning 60 of the concentrator belt is of the utmost importance in the practical operation of the device, in that by so cushioning the same I provide for a thorough separation of the gangue from the values, and the deposit of the latter in the riffles 75 where they will remain 65 without danger of being jarred out because

of undue shocks which result necessarily with an uncushioned separator. The gangue passing down the belt 20 is discharged upon the screw conveyer 5 and upon that side of the partition 4 and is conveyed 70 through a suitable aperture in the side of the tank to the bucket conveyer 6 in the casing 7, whereby it is elevated and discharged in any suitable manner. This elevation and discharge of concentrates in a 75 similar manner is accomplished by the buckets 11 in casing 12, which receive and remove the values fed through one side of the machine by the screw conveyer 10.

In employing a concentrating belt or 80 table submerged in liquid, it is highly important, first, that the operative parts be so disposed with respect to the belt or table that no grease from the same will drop upon the belt or table, and further that the operative parts immersed in the liquid be reduced to a minimum. It will be observed that in my present construction, the main shaft 34 and its allied parts are disposed outside of the tank, while the operating vibrating 85 mechanism, while disposed inside of the tank 1, is located to one side of the belt proper, thereby reducing the danger of grease and oils to a minimum. Furthermore, by employing the bell crank 49, I 90 have reduced the rotating parts immersed in the liquid to a minimum, as the employment of an eccentric at this point would increase materially the undue wear and friction due to its immersion in gritty liquid, 95 such as is found in these devices. Again by disposing the operative mechanism in the manner shown, I have provided for driving all of the parts without the necessity of a side penetration of the tank 1, thereby 100 eliminating all stuffing boxes and devices of that character, necessarily producing undue friction and wear.

In Fig. 6, I have shown a diagrammatic view of my improved concentrator in connection with a wet screen. It will be understood that the material to be treated will respond more readily to the separating action if submitted to the concentrator in a wet state, and when placer material is being 110 treated taken from a bank or bed of a stream, it is necessary that it be screened before it is introduced into the concentrator to remove the larger materials. In order to present the material in a wet state to the 115 concentrator, and at the same time to obviate the waste of water, which in certain localities is a desideratum, I provide for screening the material with water taken from the tank 1, the said water being discharged, together with the screened material, back into the concentrator tank. Thus, 120 I mount the screen 75, which may be of any suitable construction, and driven in any suitable manner, so as to discharge upon the 125 130

table 74 of the chute 73 and connect said screen by means of a pipe 76 and an interposed pump 77 with the side of the tank 1, so that water may be drawn from said tank by said pump and forced into the screen 75 from whence it will be discharged together with the screened material back into the tank 1 through the chute 73. I have found in practice that while it is highly essential 10 that the water in the tank 1 should be in a quiescent state during the operation of the concentrating belt, that the withdrawal of the water through the pipe 76 necessary for the screening operation will in no wise dis- 15 turb the volume of water in the tank, at least to an extent to interfere with the effective operation of the concentrating device.

I also contemplate the employment of my 20 improved concentrating tank as well as the screening device 75 in connection with a suitable dredge or shovel (not shown), said dredge or shovel being mounted upon wheels to run on the track 3 with the tank 1, but 25 being disposed in front of said tank and its screen 75 in such position that it may discharge directly into said screen 75. By this assemblage of units, I provide for an uninterrupted operation of the device from the 30 picking up of the material to be treated to its discharge separated as concentrates and gangue from the tank 1.

I have shown and described my improvements as particularly adapted for use in 35 connection with an endless belt concentrator submerged in a body of still water or other liquid, but I wish it to be understood that I do not limit myself to this application of the various novel features of the invention, 40 as the same may be applied with equally advantageous results to a concentrating belt not immersed in liquid, or even to a concentrating table.

Having thus described my invention, what 45 I claim as new and desire to secure by Letters Patent, is:—

1. In a concentrator, an endless concentrating belt, a supporting frame for the same, a fixed retainer in which said supporting frame is pivoted intermediate its length, means for suspending said supporting frame from its four corners and for cushioning said suspending means and adapted to take the weight of said belt and frame off of said 55 fixed retainer, and means for driving said belt.

2. In a concentrator, an endless concentrating belt, a supporting frame for the same, a fixed retainer in which said supporting frame is pivoted intermediate its length, means for suspending said supporting frame from its four corners and for cushioning said suspending means and adapted to take the weight of said belt and 60 frame off of said fixed retainer, means for

driving said belt, and means for imparting a vibratory movement to said belt.

3. In a concentrator, an endless concentrating belt, a supporting frame for the same, means for pivoting said supporting frame intermediate its length, means for suspending said supporting frame from its four corners and for cushioning said suspending means for resilient vertical movement, and means for driving said belt by 70 power applied initially to the axis of said intermediate pivot, thereby permitting a 75 rocking motion to said supporting frame and belt.

4. In a concentrator, an endless concentrating belt, a supporting frame for the same, means for pivoting said supporting frame intermediate its length, means for suspending said supporting frame from its four corners in a position inclined to the 80 horizontal, means for cushioning the suspension means supporting the upper ends of the frame, said suspending and cushioning means being adapted to take the weight of the frame off the pivoting means, and 85 means for driving said belt by power applied initially at the axis of the said intermediate pivot, thereby permitting a rocking motion of said supporting frame and belt. 95

5. In a concentrator, a concentrating belt, a supporting frame for the same, a transverse shaft upon which said supporting frame is fixed intermediate its length and with which it may be rocked, means for imparting a longitudinal vibratory movement to said shaft, and mechanism mounted in 100 part upon said shaft for driving said belt.

6. In a concentrator, a concentrating belt, a supporting frame for the same, a transverse shaft upon which said supporting frame is fixed intermediate its length and with which it may be rocked, means for imparting a longitudinal vibratory movement to said shaft, means for cushioning the 105 shocks in each direction of vibration, and mechanism mounted in part upon said shaft for driving said belt.

7. In a concentrator, a concentrating belt, a supporting frame for the same, a transverse shaft upon which said supporting frame is fixed intermediate its length and with which it may be rocked, means for imparting a longitudinal vibratory movement to said shaft, means for cushioning 110 the shocks in each direction of vibration, and a sprocket chain drive for said belt having certain of its sprocket wheels mounted 115 freely on said shaft.

8. In a concentrator, a concentrating belt, a supporting frame for the same, a transverse shaft upon which said supporting frame is pivoted intermediate its length, means for suspending said supporting frame from its four corners and for cushioning 125 130

said suspending means and adapted to take the weight of said belt and frame off of said transverse shaft, and means for imparting a longitudinal vibratory movement to 5 said shaft.

9. In a concentrator, a concentrating belt, a supporting frame for the same, a transverse shaft upon which said supporting frame is pivoted intermediate its length, 10 means for suspending said supporting frame from its four corners and for cushioning said suspending means and adapted to take the weight of said belt and frame off of said transverse shaft, means for imparting a longitudinal vibratory movement to said shaft, and means for cushioning the shocks in 15 each direction of vibration.

10. In a concentrator, an endless concentrating belt, means for driving the same, a 20 supporting frame for said belt, a transverse shaft upon which said frame is pivoted intermediate its length, a power shaft, a rod reciprocated from said power shaft, a bell crank reciprocated by said rod, connections 25 between said bell crank and the pivotal shaft

of said frame, and springs interposed between said bell crank and said pivot shaft for cushioning the vibratory movement imparted to said shaft in each direction.

11. In a concentrator, a fluid containing 30 tank, an endless concentrating belt therein, means for driving said belt, a supporting frame for said belt, a transverse shaft upon which said frame is pivoted intermediate its length, a power shaft disposed at the top of said tank, a rod reciprocated from said power shaft and extended into the tank, a bell crank reciprocated by said rod, connections 35 between said bell crank and the pivot shaft of said frame, and springs interposed between said bell crank and said pivot shaft 40 for cushioning the vibratory movement imparted to said shaft in each direction.

In testimony whereof I have hereunto set my hand in the presence of two subscribing 45 witnesses.

FRANK O. STERRETT.
